MIXING MACHINE

Oystein Jacobsen, Montgomery County, Ohio, assignor to The Duriron Company, Inc., Dayton, Ohio, a corporation of New York

Application August 12, 1940, Serial No. 352,238

6 Claims. (Cl. 259—96)

The present invention relates to mixers or stirrers, and particularly to those of the rotating continuous type.

The primary object of the invention is to provide an efficient mixer or agitator of the rotary type, which will accommodate large quantities of materials or fluids and in which the proportions of the mixture ingredients may be readily changed.

Another object is to provide a rotary mixer in which the degree or amount of mixing or agitating is controlled entirely apart and independently of the speed of rotation of the mixer. Consequently, a prime mover of constant speed may be employed.

The final object is to provide a mixer or stirrer in which the fluids or materials to be mixed are drawn under pressure into the mixture, and the mixture leaves the machine with considerable pressure or velocity.

The invention will be better understood when the following specification is perused in connection with the accompanying drawings.

In the drawings:

Figure 1 is a longitudinal sectional view, partly in elevation, of the improved mixing and stirring machine.

Figure 2 is an enlarged fragmentary sectional view of the machine, but showing more particularly the details of the impeller and the mechanism by which the amount of fluid recirculation and mixing are controlled.

Figure 3 is a perspective view of the impeller, looking at the vertical edge and with a portion cut away to expose the interior.

Figure 4 is a central cross section, partly in elevation, of the machine taken along the line 4—4 in Figure 1.

General arrangement

In general, the improved machine of this invention is designed to mix fluids, such as sulphuric acid and water, or nitric acid and water, also fluid-like materials, as for example, when it is desired to mix water, bleaching or chemical agents with pulp during the manufacture of news print or chemical liquors with particles of solid material and to draw these fluids or solid materials by strong suction effect into the mixer, wherein they are thoroughly mixed, and finally to expel the mixed fluids or materials at a high velocity or high pressure, or both. Hitherto, difficulty has been experienced in the design and construction of mixing machines which operate by rotation and which handle corrosive fluids as

one or more of the mixture ingredients, and even more difficulty is present when large quantities of such material or fluids must be handled as a continuous process, and the degree of mixing must be readily controllable from a position exterior of the mixing machine.

In general, my invention contemplates a mixing machine which is constituted of three essential parts, namely, an impeller having two portions, one of which serves to produce a considerable suction effect on the mixture ingredients and the other of which serves to recirculate the ingredients within the machine, thereby assuring a thorough mixing effect; the casing which is so designed as to permit the mixture ingredients to be readily admitted and also to allow these ingredients to be recirculated from the casing, through the impeller and back to the casing in recirculatory paths; and finally a mechanical adjustment means by which the axial position of the impeller within the casing is changed to control the amount of the mixture which is caused to be recirculated. In order to successfully withstand the corrosive effects of any acids that may be employed as one or more of the mixture ingredients, those parts of the machine with which the mixture comes into contact are made of acid-resisting material, such as high silicon iron or alloy steel.

Construction

Referring to the drawings in detail, the casing which houses the impeller is designated generally by the reference character 1. This casing is constituted of a side plate 2, fabricated as a heavy casting of acid resistant iron in case acids are being handled, and is formed with a peripheral flange which takes the shape of a volute, as shown in Figure 4. This flange is designated by the numeral 3. The space within the flanged portion of the casing is drawn down to a neck, shown at 4, which terminates in an enlarged portion 5. The opening in the neck portion is preferably circular. There is a clamping ring 6 which bears against the under side of the enlarged portion 5, the purpose of which is to permit connection with a similar ring attached to an outgoing conduit (not shown). The central portion of the side plate 2 is provided with an outwardly extending hub 7, provided with an internal bore which terminates at its right-hand end (Figure 1) in an inwardly projecting shoulder 8.

The opposite side plate 9 of the casing is also constituted as a heavy casting of acid resistant

iron when acids are being handled. The casting is provided at its outer periphery with an annular shoulder portion 10, leaving a bearing surface 11 which abuts a corresponding surface on the flanged portion 3 of the casing. The side plate 9 is provided with a relatively large hub-like extension 12, cored out to leave an inlet passageway or chamber 13. The inlet passageway or chamber 13 has a bore 14 machined to size, the purpose of which will be explained presently. A two-way coupling 15 is secured at the plate 16 to the extension 12, this coupling being connected through a shut-off valve 17 to a pipe 18 at one side, and to a pipe 19 through a valve 20 at the other side.

The two side plates 2 and 9 of the casing may be secured together in any suitable manner. However, inasmuch as these castings may be made of silicon iron which is not readily machinable, the two casing parts are closed, preferably by means of a clamping structure. This structure is formed of two rings 21, 22, disposed on opposite sides of the casing, which have openings to receive bolts 23, the shape of the rings and the position of these openings being such that the bolts 23 will clear the casing. The bolts are provided with nuts 24 which upon being tightened will serve to clamp the two sides of the casing 2, 9 together, preferably rendering the joint indicated at 11 completely fluid-tight. The volute-shaped portion of the casing is provided at the bottom with a drainage aperture 25, closed by a cover plate 26 and secured to the casing extension 27 by means of the U-bolt 28.

The impeller is designated generally by the reference character 29, and consists of a central hub 30, disc-like side walls 31 and 32 and spirally directed impeller vanes 33 (Figure 4). The hub 30 is provided with outwardly curved surfaces 34, 35 forming respectively main and auxiliary inlet passages 36 and 37, with curved inner surfaces 38, 39 of the impeller discs 31 and 32. The curved surfaces 38 and 39 are additionally rounded at their entrance portions 40 and 41 so as to increase the efficiency of inward flow by taking care of the *vena contracta* effect. The hub 30 at its periphery 42 thus forms a partition separating the intake passageways 36 and 37, and likewise serving as a support for the remainder of the impeller by being joined as at 43 to the vanes 33.

The hub 30 of the impeller is carried on a shoulder portion 44 of a shaft 45, and secured thereto in any suitable and well known manner. A sleeve 46 surrounds the shaft 45, this sleeve having a diameter as rotatably to fit within the annular shoulder 8 of the casing. There are discs 47 of packing material contained within the cored-out hub 7, these discs being held in place by a gland 48 secured to the hub 7 by means of bolts 49. The shaft 45 is carried by an end bearing 50 and an intermediate bearing 51, of which only one has been shown in detail.

The bearing 51 is preferably of a ball bearing type, and is supported on a web 52 which extends radially outward to meet a frame 53 which extends to the left from the side plate 2 of the casing, to which it may be secured in any suitable manner. As illustrated, the ring 22 is integral with an annular portion 54 of the frame so that by tightening the nuts 24 the frame is rigidly secured to the casing as well as clamping the two halves of the casing together. The lower part of the frame 53 is carried on a base 55, provided with bosses 56 for bolting to the floor. The left-

hand end of the frame 53, as seen in Figure 1, carries the end bearing 50, which is also so constructed as to provide an axial movement of the shaft 45 and of the impeller connected to the shaft.

For maintaining the bearing in position the frame 53 is provided with an inwardly extending flanged portion 57 having a circular groove for receiving a circular ball race, indicated at 58, with ball bearings 59. The inner side of the ball race 58 is held against a shoulder provided on the flange 57 by a retaining plate 60, which is bolted as indicated at 61 to the frame. The plate 60 is provided with a relatively large bore, grooved 15 as indicated at 62, and is adapted to receive a sleeve 63. This sleeve terminates at one end in a hand wheel 64 and at the other end is provided with a shoulder against which the lower ball race 65 fits, the latter being held in position by a ring 20 66 which is screwed on a threaded end portion of the sleeve 63. The hand wheel 64 has a bore provided with threads which fit into corresponding threads of a threaded portion 67 of the shaft 45. The latter is extended beyond the threaded portion 25 to receive a coupling 68, keyed thereto as indicated at 69. This coupling is for the purpose of making mechanical connection between the shaft 45 and an external source of mechanical power, such as an electric motor (not shown). There 30 is a web 70 joining the flanged portion 57 and the bearing 51, the purpose of which together with the flange 52, is to form an oil-tight compartment between the bearings. Oil may be introduced into the compartment through an opening in the 35 boss 71, and the height of the oil may be visually determined at the sight 72. The oil is kept at such a level in the compartment as to find access to both bearings 51 and 50.

From the foregoing it is evident that when 40 a rotary effort is applied to the coupling 68, the shaft 45 will rotate and carry with it the hand wheel 64 and sleeve 63, together with the lower ball race 65. Consequently, there is no relative motion between the threads on the hand wheel 45 and the threads 67 on the shaft. However, assuming that the shaft 45 is stationary, it is apparent that rotation of the hand wheel 64 will cause the sleeve 63 to be rotated, carrying with it the lower ball race 65 but without any relative 50 longitudinal movement with respect to the frame 53. It will be noted that the groove 62 in the plate 60 serves to reduce friction at this point to a minimum when the sleeve 63 is turned. However, turning the hand wheel 64 relative to the stationary shaft causes the latter to move right or left due to the threaded portion 67, and depending on the direction in which the hand wheel 55 is turned. Thus the axial position of the impeller 60 within the casing can be directly controlled by the movement of the hand wheel 64. In order to lock the hand wheel in any desired position with respect to the shaft, a locking bolt 73 is provided which carries a shoe 74 provided with threads bearing against the threaded portion of the shaft. It will be understood that when the bolt 73 is tightened the shoe 74 will prevent any longitudinal movement of the sleeve 63 with respect to the shaft, and thus prevent rotation 65 of the hand wheel.

Figure 1 shows the impeller at its extreme left-hand position, as determined by the hand wheel 64, while Figure 2 shows the impeller at its extreme right-hand position, the hand wheel 75 in the mean time having been rotated to cause

the impeller to move from left to right within the casing. It will be understood that the casing of the machine is considerably wider than the width of the impeller so as to permit a substantial movement of the latter in an axial direction. The side wall 31 of the impeller is provided with a flat surface 75 which bears against a corresponding surface 76 of the casing when the impeller is at its extreme left-hand position. The side wall 32 of the impeller terminates at the center in a relatively long neck portion 77 which fits snugly within the bore 14 of the side plate 9 of the casing, and is provided with a shoulder 78 which bears against a corresponding shoulder 79 of the casing when the impeller has been moved to its extreme right-hand position.

Operation

Let us assume that it is desired thoroughly to mix sulphuric acid and water in the improved machine. The water is first admitted through the pipe 18 with the valve 17 open, and the acid is admitted through the pipe 19 and the valve 20 to the T-shaped coupling 15. The two liquids pass through the inlet passageway 13 and enter the neck portion 77 of the impeller. Assuming that the impeller is being rotated counter-clockwise, as seen in Figure 4, the vanes 33 will introduce a strong suction on the two entering liquids, causing these liquids to move from the center of the impeller through the vane passageways and to leave the impeller at the periphery thereof. A certain amount of agitation or mixing of the two liquids takes place within the impeller under these circumstances, but for certain types of usage the mixing effect obtained in this manner is not sufficient. This would be particularly true in case a liquid, such as an acid, were introduced through one of the incoming pipes and a semi-solid material, such as pulp or a granulated material such as carbon dust, were introduced through the opposite pipe.

Whereas in the prior-art forms of pumps, in order to increase the rate of mixing it was necessary to change the speed of the impeller, in accordance with my improved machine the mixing rate can be either increased or decreased depending on the requirements, without the slightest change in the speed of the impeller. This improvement is brought about by the use of a recirculatory path for the mixture contained within the machine, and effected by a longitudinal movement of the impeller.

Referring now to Figure 2 in which the impeller has been moved to its extreme right-hand position by the hand wheel 64, it will be noted that the combined fluids first pass through the annular passageway 36 and then through the vane compartments, but upon leaving the periphery of the impeller a large portion if not all of the combined fluid is caused to pass downwardly between the surfaces 75, 76, due to the suction effect introduced by the vane portions to the left of the inner hub surface. This fluid is drawn through the passageway 37 and again introduced to the vane compartments, where it combines with the other fluid which has flowed through the passageway 36. Consequently, there is a direct mixing effect caused by that portion of the vanes to the right of the hub surface 34, and a recirculated or regenerated mixing effect introduced by the vane portions to the left of the hub surface, causing the fluids to be thoroughly mixed by the combined action of the direct mixing effect introduced by a portion of

the vanes, and a recirculatory mixing effect introduced by other portions of the vanes, all of these effects being cumulative within the impeller. As great or as little of the fluid may be subjected to the recirculatory effect depending on the space left between the surface 75 of the impeller and the surface 76 of the casing, which in turn depends on the adjustment of the hand wheel 64.

In its preferred mode of operation the pump is rotated continually to mix two or more liquids, acids, etc. which have passed through the pipes 18, 19 by opening the valves 17, 20. The rate of mixing depends not only on the speed with which the impeller is rotated but also on the position of the impeller with respect to the casing. In case the impeller is moved a predetermined distance to the right (Figure 1) the fluid leaving the periphery of the impeller will be drawn downwardly to the left of the impeller, as indicated in Figure 2, and will be caused to enter the impeller again through its left-hand inlet. This recirculation of the fluid causes the ingredients of the mixture to be thoroughly intermixed so that when the fluid is finally ejected at the outlet passageway 30, the elements of the mixture have been thoroughly incorporated with one another. It is apparent that a mixer of this character can handle large quantities of fluids in that the rate with which the mixed fluid leaves the machine is equal to the rate with which the fluids to be mixed enter the machine.

If desired the improved machine may be employed for intermittent operation in which independent charges are admitted successively to the machine through the pipes 18, 19. Assuming that the first charge has been admitted to the machine and that the valve in the outgoing pipe has been closed except for a vent opening, the impeller is rotated at a predetermined speed and so adjusted with respect to the casing as to provide the proper amount of recirculatory effect. Upon conclusion of the mixing operation the mixed fluid may be drained from the casing through the opening 25 after the cover plate 26 has been removed. The pump may then be primed in any suitable and well known manner, ready to receive the next charge of fluid to be mixed.

The operation of the machine is exactly the same when semi-solids are being mixed instead of fluids. The machine may be operated either continually or intermittently, as explained above. In the case of mashing and bleaching pulp by the use of acids, it is apparent that by operating the hand wheel 64 the mixing rate can be so adjusted as to exercise a careful control over the rate and the amount of mashing and bleaching that is given to the pulp. Many other desirable effects may be obtained by regulating the size of the recirculatory path between the impeller and the casing, and depending on the character of the materials that are introduced into the mixing machine. While it is preferred that the machine be stopped when the axial position of the impeller is being regulated at the hand wheel 64, it may on occasion be entirely practical to provide mechanism known to those skilled in the art, by which the shaft 45 may be moved in an axial direction during operation of the impeller, thus eliminating the necessity for shutting the machine down for adjustment.

It has been pointed out that the improved machine is adapted to mix two or more fluids, or one fluid and a semi-solid or granular material, so

that the terms "fluid" or "fluid-like materials" set forth in the claims are intended to be sufficiently broad to read on a fluid, a semi-solid or a semi-fluid material.

It will be understood that I desire to comprehend within my invention such modifications as come within the scope of the claims and the invention.

Having thus fully described my invention, what I claim as new and desire to secure by Letters Patent, is:

1. A rotary mixing machine for fluids comprising a casing containing a rotary impeller, said impeller having a hub dividing the central portion thereof into oppositely directed intake passageways which lead to an outward passageway, means for presenting all of the fluids into one of said passageways to be mixed by the impeller, and means for presenting at least a part of the mixed fluid through a recirculatory path within the casing to the other of said passageways whereby the fluids are recirculated through the impeller and are in a thoroughly mixed condition when leaving the machine.

2. A rotary mixing machine for fluids comprising a casing containing a rotary impeller, said impeller having a hub dividing the central portion thereof into oppositely directed intake passageways which lead to an outward passageway, means for presenting all of the fluids into one of said passageways to be mixed by the impeller, means for presenting at least a part of the mixed fluid through a recirculatory path within the casing to the other of said passageways whereby the fluids are recirculated through the impeller and are in a thoroughly mixed condition when leaving the machine, said casing being of greater width than the impeller, and means for shifting the impeller along its axis with respect to the casing whereby the amount of recirculated fluid is changed and the degree of mixing is controlled.

3. A rotary mixing machine, for fluids comprising a casing containing a rotary impeller, said impeller having a hub dividing the central portion thereof into oppositely directed intake passageways which lead to an outward passageway, means for presenting all of the fluids into one of said passageways to be mixed by the impeller, means for presenting at least a part of the mixed fluid through a recirculatory path within the casing to the other of said passageways whereby the fluids are recirculated through the impeller

and are in a thoroughly mixed condition when leaving the machine, a shaft secured to said hub, said casing being of greater width than the impeller, and means for moving said shaft axially to shift the impeller with respect to the casing whereby the amount of recirculated fluid is changed and the degree of mixing is controlled.

4. A rotary mixing machine comprising a casing containing a rotary impeller, said impeller including means for directing fluid-like materials outwardly from opposite sides of the impeller, means for presenting all of the materials to be mixed to one side of the impeller, and means for presenting the materials which have been given a preliminary mixing by the impeller through a recirculatory path within the casing to the other side of the impeller whereby the materials are recirculated through the impeller and are thoroughly in a mixed condition when leaving the machine.

5. A rotary mixer comprising a casing containing a rotary impeller, said impeller including a plurality of arcuate vanes and adapted to receive fluids to be mixed into opposite sides of the impeller, said fluids leading the impeller at the outer tips of the vanes, said impeller being adapted to be shifted along its axis within the casing to cause fluid in different amounts to be received by the opposite sides of the impeller and to pass through a recirculatory path within the casing whereby the degree of mixing of the fluids is determined by the position of the impeller with respect to the casing.

6. A rotary mixer comprising a casing containing a rotary impeller, said impeller including a pair of plates separated by vanes the inner portions of which communicate with an inlet passageway and the outer portions communicate with an outlet passageway, said impeller having a width less than the width of the casing, means for adjustably positioning the impeller within the casing so as to leave a space between the impeller and the casing at the side opposite said inlet passageway, and means for presenting fluids to be mixed to the inlet passageway whereby as the impeller rotates the mixed fluid leaving the impeller is caused to pass through said space between the impeller and the casing and to recirculate through the vanes and entirely within the casing in order thoroughly to mix the fluids within the impeller.

OYSTEIN JACOBSEN.
